UNITED STATES PATENT OFFICE

2,007,936

APPARATUS FOR PRODUCING AND MODULATING AN IONIC DISCHARGE

Samuel Ruben, New Rochelle, N. Y., assignor to
Sirian Lamp Company, Newark, N. J., a corporation of Delaware

Application July 31, 1930, Serial No. 471,977

5 Claims. (Cl. 176—1)

This invention relates to ionic discharge devices and particularly to such a device in which the discharge may be modulated so that it lends itself for use in producing modulated lighting effects as in television, sound-on-film apparatus, signaling devices, or other devices using rapid changes in light intensity.

Heretofore for the production of modulated light, especially in devices having radiation in the actinic part of the spectrum, a low pressure gas discharge between two electrodes has been employed requiring a high voltage to operate, modulation being accomplished by superimposing an audio frequency oscillation on the supply current leads. This type of discharge is limited in intensity due to localization effects which are common with high intensity arcs or low pressure discharges and require an elaborate equipment for the generation of the necessary high voltage discharge.

It is therefore one of the objects of the present invention to produce an intense ionic discharge of such a character that it may be modulated without lag at the higher audio frequencies.

Another object of the invention is to provide a light capable of producing an intense ionic discharge at relatively low voltages.

Another object of the invention is to provide a system for modulating a high intensity discharge by relatively minute electrical variations.

Other objects of the invention and objects relating particularly to the method of manufacturing and assembling the various parts and to the circuits for using the device will be apparent as the description of the invention proceeds.

Several embodiments of the invention have been illustrated in the accompanying drawings in which:

Fig. 1 is a schematic showing of a system for producing an image on a screen for television and including a side elevational view of the lamp for producing the light;

Fig. 1a is an enlarged longitudinal sectional elevation of the electron emitting element;

Fig. 2 is a diagram of a system for producing a sound wave on a sensitized moving picture film; and

Fig. 3 shows a circuit adapted for use in a visible signaling system.

Referring now more specifically to the drawings, one embodiment of the lamp of the invention is illustrated in Fig. 1 and comprises an envelope 10 having the usual press 11 formed integral with the envelope and upon which the elements of the lamp are mounted. A coil 12 of re-

sistance wire is coated with an electron emitting material 13. The coil may be of any desired resistance material but preferably of a refractory metal such as tungsten to increase the light output of the lamp and the electron emitting material may be the oxides of barium, strontium, calcium, magnesium, or any other material which tends to increase the emission of electrons from a body. The coil 12 may be supported at its lower end upon a short support rod 14 which is sealed in the press 11 while the upper end of the coil may be supported upon a rod 15 which may be bent outwardly and downwardly and may also be sealed in the press 11. Leading-in wires 16 and 17 may be attached respectively to the rods 15 and 14 to connect the filament in a suitable circuit. A support rod 18 may be mounted substantially parallel to the coil 12 and may be provided with a series of rings 18a which extend around the coil 12 in spaced relation along the length thereof and may be welded to the support 18. The support 18 and rings 18a form the modulating grid 19. The support rod 18 may extend downwardly and may also be sealed in the press 11 and a leading-in wire 20 may be connected to it as indicated.

The envelope 10 is filled with a suitable inert gas, preferably a monatomic gas such as neon, argon, helium, krypton, xenon, and the like or mixtures of these gases and also a low pressure of metal vapor such as cesium or mercury vapor may be added if desired, the pressure in the bulb being in the neighborhood of 200 mm. of mercury. This pressure of the gas in the bulb appears to depend somewhat upon the voltage used and higher pressures may be used if a higher voltage is contemplated. The pressure of the gas should be sufficient in any case to restrict the ionic discharge when the filament is energized to the vicinity of the filament so that a halo of intense illumination is formed along the length of the filament and within a short distance of it.

Any desired number of filaments may be used in the lamp and these may be arranged in any desired shape or configuration although I have described and shown a single straight filament for purposes of convenience. Where it is desired to use the lamp on a 110 volt circuit, for instance, it may be preferable to have as many as four such filaments mounted in series and spaced about a common central axis.

Care should be taken in exhausting the lamp that all undesirable gases and vapors are removed from the envelope. The envelope with the press and elements mounted as indicated in the figure

- may be connected to an exhaust pump in the usual manner and an oven placed over it to raise the temperature thereof to between 350 to 400° C. or to as high a temperature as the glass will stand 5 without softening. A current may be run through the filament at this time to heat it to a red heat at a temperature of about 600° C. and the heat and exhausting may be continued until there is no fluorescence when a high tension current from 10 an induction coil is directed against the walls of the envelope or in other words until there is no more gas inside of the envelope. This process is continued until a high vacuum of about .5 micron is obtained. Current is then increased 15 through the filament until the temperature thereof is slowly raised to about 800° C. with a bright red color. This drives out the binder in the electron emitting material and other occluded gases which may be present.
- 20 When no more gas is found in the bulb, the oven may be raised and the filament heated to about 1200° C. or slightly less, the pump being connected all this time to maintain a high vacuum. The pump may then be shut off, the filament current turned off, and a slight amount of neon gas (about $\frac{1}{2}$ mm.) may be admitted to the envelope and the filament current turned on again and gradually increased. Spots of localized discharge will then appear having a reddish color and these 25 spots will gradually spread until a diffused glow completely fills the envelope. This process activates the electron emitting coating and is maintained until the discharge is uniform throughout the entire bulb which usually takes less than 30 ten minutes when the activation is completed. During this time the current on the filament should not be raised too high so that the coating will not be destroyed or thrown off from the filament. If white discharge spots appear on the 35 filament or support rod it is an indication that there are more gases and vapors in the bulb and the bulb should again be exhausted and the whole process of activation repeated. In the activating process the support rod 15 and other metal 40 parts in the envelope as well as parts of the filament itself aid in the activation as they act as cooperating electrodes having a different potential than the potential of any given portion of the filament and coating.
- 45 When the activation is completed the filament temperature may be raised for a moment to about 1400° C. and then the vacuum pump may be again connected and the gas pumped out to remove any undesirable gases which have been thrown off 50 during the activation process. The filament circuit may then be disconnected, the pump turned off, and the desired gases admitted into the envelope. In one instance a mixture of 50 mm. of neon and 150 mm. of argon were found to give 55 good results. The bulb may then be sealed off after which a small quantity of magnesium which has been placed in a suitable container, as 47 mounted, for instance, on the support rod 15, may be flashed to absorb any impurities. The bulb 60 may then be ready for use.
- 65 The metallic vapor may be introduced when the magnesium is flashed by providing a salt of the desired metal in the container with the magnesium. Thus if caesium chloride is placed in the 70 container, caesium will be liberated leaving magnesium chloride which is a stable salt.
- The leading-in wires 16 and 17 for the coil 12 or filament of the lamp may be connected by means of the wires 21 and 22 respectively to a 75 generator 23 for producing direct current for en-

ergization of the filament. A choke coil 24 may be included in the circuit of the wire 22 and condensers 25 and 26 may be connected across the leads 21 and 22 one at each side of the choke coil 24 in a manner well-known in the art to assist in smoothing out any variations caused by the generator. The modulating grid 19 may be connected by means of a wire 27, connected to the leading-in wire 20, to one end of the secondary 28 of a transformer 29. The other end of the secondary 10 may be connected to a biasing battery 30, the positive side of which may be connected to the midpoint of a resistance 31 which may be connected between the line wires 21 and 22 by means of wires 32 and 33 respectively. Filtering condensers 34 and 35 may also be connected between the positive side of the battery 30 and the ends of the resistance 31. The primary 36 of the transformer 29 may be connected to the output of an amplifier or other signal source. When an incoming signal is impressed on the primary 36 of the transformer 29 it affects the secondary 28 and varies the potential on the modulating grid 19 which can never become positive due to the biasing battery 30.

25 When the current is turned on current flows through the wires 21 and 22, through the support rods 15 and 14, and through the refractory metal coil 12 thereby raising the temperature thereof sufficiently to cause it to emit electrons as described in the above mentioned co-pending application. The pressure of the gas in the envelope 10 and the voltage across the filament 12 is sufficient to cause an ionic discharge extending out from the filament and 30 lengthwise thereof. This discharge appears along the filament like a halo and is intensely bright, giving an intense white illumination.

When the charge on the modulating grid is negative the tendency is to cause the halo formed 40 around the filament to draw in upon the filament and when the grid is charged positively it tends to pull the halo out from the filament increasing its cross-sectional area. In other words, as the potential of the modulated grid is varied the halo 45 around the filament expands and contracts thus varying the intensity of the light produced. Inasmuch as the electron emission from the coated filament is easily controlled by the slightest potential change of the modulating grid the ionization 50 of the gas is as easily controlled as it depends on the electron emission from the filament and hence the light is caused to vary in accordance with the modulation of potential upon the grid.

55 A suitable television apparatus as shown in Fig. 1 may be provided for using such a light to transmit an image electrically and project it upon a screen. In this apparatus the light from the lamp may be directed or converged by means of a lens 37 upon a scanning disc 38 which rotates in front of the lens and is provided with the usual series of holes formed in a spiral path so that the light projected through the disc is moved across the screen in successive horizontal lines. A suitable 60 lens system 40 may be provided to converge or project the image of the hole in the scanning disc upon a screen 41. When the primary 36 of the transformer 29 is suitably connected to a light-sensitive cell exposed to light reflected from an 65 object through a scanning disc similar to that shown at 39 and rotating in synchrony therewith, the object will be reproduced upon the screen 41.

In Fig. 2 I have shown a system whereby the lamp may be used for recording sound on a moving 70

picture or other type of film. Here the lamp and circuit are exactly similar to what has been shown in Fig. 1 but in place of the scanning disc an aperture plate 42 is shown having an aperture 43 against which the light is directed by means of the lens 37, the lens system 44 being used to project a picture of the lighted aperture 43 upon the film 45 which is caused to move at a uniform rate in the plane upon which the light is focused. When a microphone or other apparatus for translating sound into electrical impulses is suitably connected to the primary 36 of the transformer 29 an accurate record of the sound is produced on the sensitive surface of the film.

In some instances it may be desired to use the lamp as a signal light as for instance for ship to ship signaling in which case the light is modulated in accordance with a telegraph and due to the nature of the light produced may be read at considerable distance by any one familiar with the code who can see the light. In such a signaling system the construction of Fig. 3 may be used. In this diagram the connections for the lamp are the same as in the preceding figures with the exception that a telegraph key 46 is used in place of the transformer 29 so that the key is connected between the wire 20 which forms the lead for the modulating grid and the biasing battery 30. Depressing the key 46 places a negative charge upon the control grid of the light and causes the discharge halo to contract more closely against the filament with the result that the light is cut down while as soon as the circuit is opened by releasing the key 46 this negative potential is removed from the control grid and the discharge halo immediately increases thereby increasing the light intensity. Heretofore it has been impossible to find a lamp which can be used for this purpose due to the thermal lag in present day lamps which is too great to transmit modulation even as slow as a telegraph code. Such signaling has been accomplished by the use of movable shutters to control the light in accordance with the dot and dashes of the code. With the present invention, however, the circuit is greatly simplified doing away with all mechanical devices and due to the light intensity of the light produced the light can be seen very much further than anything which is now in use.

The lamp may also be used successfully wherever modulated light is desired, as for instance in advertising, to provide an intermittently flashing sign.

While the invention has been described particularly in connection with an electric light it is to be understood that it is applicable under any conditions where an ionic discharge is desired to be controlled by varying the potential on an adjacent electrode.

Many modifications of the invention may be

resorted to without departing from the spirit thereof, and I do not desire to limit the invention therefore except as such limitations occur in the appended claims.

What I claim is:

1. An electron discharge device comprising a member capable of emitting electrons when heated, an inert ionizable gas surrounding said member, said gas being at such a pressure that a luminous discharge takes place along the element when a potential is impressed on the element which brings the temperature thereof to the point of profuse electron emission and which exceeds the breakdown potential of the ionized gas, and means adjacent said element for controlling the discharge from said element.

2. An electron discharge device comprising an envelope, a filamentary conductor within said envelope, an electron emitting coating on said conductor, an ionizable gas surrounding said conductor, the pressure of said gas being sufficient to restrict the densely ionized portion of said gas to the vicinity of said electron emitting coating when said coating is raised to electron emitting temperature and the potential drop along the conductor exceeds that of the ionized gas layer, and a control conductor in the vicinity of said filamentary conductor.

3. An electrical discharge device comprising an envelope, a filamentary conductor within said envelope, an electron emitting coating on said conductor, a mixture of neon and argon gas surrounding said conductor within said envelope, the pressure of said gas being sufficient to confine the densely ionized portion thereof to the vicinity of said conductor when said conductor is raised to an electron emitting temperature and the potential drop along the conductor exceeds that of the ionized gas layer, and a control conductor in the vicinity of said filamentary conductor.

4. An electric lamp comprising an envelope, a filamentary conductor within said envelope wound in the form of a helix, a coating of electron emitting material on said conductor, and an ionizable gas within said envelope, and having a pressure such that the dense ionization of said gas is confined to the vicinity of a portion of said conductor in a tubular sheath surrounding said conductor, and a control conductor in the vicinity of said first mentioned conductor, said control conductor including a support rod and a plurality of rings surrounding said filamentary conductor.

5. In a device of the class described an elongated electron emitting element, an ionizable gas surrounding said element said gas having a pressure sufficient to confine the ionization thereof to the vicinity of said element, and a plurality of wire loops surrounding said element and connected electrically together.

SAMUEL RUBEN. 60
